THROTTLE CONTROLS FOR INTERNAL COMBUSTION ENGINES

Johan Lichtenstein, Levallois-Perret, France,
assignor to Societe Generale des Carburateurs
Zenith, Geneva, Switzerland

Application September 26, 1938, Serial No. 231,841
In France October 1, 1937

10 Claims. (Cl. 137—139)

The present invention relates to an improved throttle control device for internal combustion engines.

The throttle of an internal combustion engine is normally controlled by the pilot, but on occasion it is necessary to superimpose a second control which limits the maximum opening which the throttle can be opened by the pilot. For example, if it is desired to regulate the engine speed within a predetermined limit, the throttle is controlled both by the pilot and by a speed governor. In aviation engines capable of developing their full power up to a predetermined altitude, the throttle is controlled both by the pilot and by a boost or limiting control which limits the maximum opening of the throttle in such a way that the induction pressure at lower altitudes cannot exceed the maximum permissible induction pressure.

In the usual throttle control devices, the combined control is realized in such a way that the displacements of the pilot's throttle control and the limiting control are added to each other to determine the final position of the throttle. For example, the pilot's control lever is capable of varying the opening of the throttle between 0° (closed position or idling position) and 90°. If the running conditions are such that the limiting control determining the maximum opening prohibits a throttle opening greater than 70°, the opening of the throttle will be 70° when the lever of the pilot's control occupies the position of maximum opening and it will be reduced to 40° if the pilot moves the control lever an amount which corresponds to a variation in the opening of the throttle of 30°. These devices have the following inconvenience: when the pilot requires to close the throttle completely to obtain slow running of the engine, the lever of the pilot's throttle control is not actually in the closed position. When the conditions of running change in such a way that the permissible opening of the throttle regulated by the limiting control is increased, the throttle opens whether it is the pilot's desire or not. Referring again to the above example, the throttle may be brought to the closed position by a displacement of the pilot's throttle control lever corresponding to a rotation of the throttle of 70° from the position of maximum opening. If the running conditions become such that the limiting control for the maximum opening allows complete opening of the throttle of 90°, the throttle will open again by 20° and the pilot will again have to move his throttle control lever

20° to bring the engine back to the slow running condition.

An object of the invention is to provide a more reliable throttle control.

Another object of the invention is to provide a 5 throttle control wherein the closed position of the throttle always corresponds to the same position of the pilot's throttle control lever whatever the position of the limiting control regulating the maximum opening.

Further objects and advantages of the invention will appear from the following description taken in conjunction with the accompanying drawings wherein:

Figs. 1 to 3 illustrate operating diagrams of a 15 device according to the invention in various phases of operation.

Fig. 4 illustrates diagrammatically in partly sectional elevation an embodiment of the invention.

Fig. 5 illustrates a section along 5—5 of the device illustrated in Fig. 4.

Figs. 6 and 7 illustrate diagrammatically in longitudinal section two modifications of the embodiment of the invention.

According to the invention, the movements of the pilot's throttle control member and the limiting control regulating the maximum opening are components but do not add to each other.

The throttle control device comprises a system 30 of two rods pivoted on each other and connected one to the throttle and the other to the pilot's throttle control at two points situated respectively on one and the other rod at an equal distance from the pivoting axis of the two rods. One of the 35 rods is in addition connected to the device for regulating the maximum opening. The connecting points of the rods with the pilot's throttle control on the one hand and with the device for regulating the maximum opening on the other 40 hand are compelled to move in two curves and the connections between one of the two rods and the throttle and between the other rod and the pilot's throttle control are such that the throttle and the throttle control occupy the slow running 45 position, when, in projection on a plan perpendicular to the pivoting axis of the rods, the said points of connection are both at the point of intersection of the curves along which they move.

The device illustrated in Figs. 1 to 3 comprises 50 an induction passage 1 controlled by the throttle 2. The throttle 2 is controlled by a lever 3 mounted on its axis. The control mechanism of the throttle 2 comprises a system of two rods 4 and 5 pivoted to each other by means of an axis 6. 55

The rod 4 is connected at a point 7 to the lever 3 by means of a link 8. The rod 5 is connected at a point 9 to the lever 10 of the pilot's throttle control by means of a link 11. The distances comprised on the two rods between the points 7 and 9 and the pivoting axis 6 are equal. The rod 4 is also connected at 12 to the control member 13 of a device 14 for regulating the maximum opening by means of a link 15. The control member 13 could be connected to the rod 5 instead of being connected to the rod 4. The displacements of the lever 10 of the pilot's throttle control are limited by a stop of maximum opening 16 and by a slow running stop 17. The points 7 and 9 of the rods 4 and 5 are compelled to move respectively along the curves 18 and 19 by means of suitable devices examples of embodiments of which will be seen from Figs. 4 to 6.

The operation of the device is the following:

- 20 In Figs. 1 and 2, the various members have been illustrated in the position they will occupy when the lever 10 of the pilot's throttle control is to be found in the position of maximum opening, i. e., in contact with the stop 16.
- 25 If the pilot displaces the lever 10 in the direction of closing and brings it to the position illustrated in broken lines in Fig. 1, the control member 13 of the device for regulating the maximum opening remaining stationary, the various members take up the positions illustrated in broken lines in Fig. 1 and the movement of the lever 10 effects a closing movement of the throttle 2.

Assuming the lever 10 to be maintained in contact with the stop 16 of maximum opening then if the control member 13 of the device for regulating the maximum opening is lowered a certain distance, the various members will take up the position illustrated in broken lines in Fig. 2 and the movement of the control member 13 of the device for regulating the maximum opening effects a reduction of the maximum opening of the throttle 2.

The length of the link 11 is selected in such a way that when the pilot brings the lever 10 into contact with the stop 17 in the slow running position as has been illustrated in Fig. 3, the point 9 of the rod 5 comes to the point of intersection 20 of the curves 18 and 19. During this movement, the point 7 of the rod 4 comes also to the point of intersection 20 of the curves, due to the equality of length of the rods between their pivoting axis 6 and their points 7 and 9. The length of the link 8 is selected in such a way that in this position the throttle 2 is in the slow running position. The rods 4 and 5 are then super-imposed, whereby the throttle 2 remains in the slow running position, whatever be the position of the control member 13 of the device for regulating the maximum opening. The movements of the control member 13 result only in pivoting the whole of the rods 4 and 5 around the point of intersection 20 of the curves 18 and 19 without having any action on the position of the throttle 2. It can thus be seen that when the pilot brings the lever 10 into the slow running position, the throttle 2 itself retains the slow running position independently of the movements which the control member 13 may effect.

In the device illustrated in Figs. 4 and 5, the ends of the rods 4 and 5 are each compelled to follow a straight path. To effect this, a rod 26 connected by a rod 27 to the lever 10 of the pilot's throttle control slides in a cylinder 28 pierced

by a slot 29. An axis 30 on which the end of the rod 5 pivots is fixed in the rod 26 and slides in the slot 29. Similarly a rod 21 connected by a rod 22 to the lever 3 mounted on the axis of the throttle 2 slides in a cylinder 23 pierced by a slot 24. An axis 25 on which the end of the rod 4 pivots is fixed to the rod 21 and slides in the slot 24.

The device for controlling the maximum opening is constituted by a boost control with a relay device of the known type. It comprises essentially a manometric capsule 31 disposed in a chamber 32 connected to the induction passage of the engine by a conduit 33. The capsule 31 controls a slide 34 of an oil pressure relay device 15 which comprises a cylinder 35 in which a piston 36 moves against a spring 37. When the slide 34 moves to the right it puts the cylinder 35 into communication with a pressure oil conduit 38 and the pressure of the oil pushes the piston 20 downwards against the action of the spring 37. When the slide 34 moves to the left it puts the cylinder 35 into communication with a conduit 39 for discharging the oil and the spring 37 pushes the piston 36 upwards driving the oil 25 contained in the cylinder 35 out through the conduit 39.

The member for controlling the maximum opening is constituted by a rod 40 fixed to the piston 36 and carrying a slide 41. The rod 4 30 is connected to the rod 40 by means of a stud 42 fixed to the rod 4 and engaging in the slide 41.

The operation of the device can be easily understood following the explanations which have been given with reference to Figs. 1 and 3. The throttle 2 is controlled both by the lever 10 of the pilot's throttle control and by the piston 36 of the boost control. If the pilot brings the lever 10 into the position of closure the two axes 30 and 25 reach the left ends of the ports 24 and 29 while 40 the throttle 2 attains the slow running position. In this position, the axes 30 and 25 are situated in extensions of each other and the rods 4 and 5 which have the same length between axes are superimposed. The whole of these two rods is 45 thus capable of turning freely about a single geometrical axis constituted by the two axes 30 and 25 and the movements of the piston 36 have no action on the opening of the throttle.

The lever 10 being placed in the position of 50 maximum opening the throttle 2 will be maintained partially closed by the boost control. If then the pilot brings the lever 10 into the slow running position the induction pressure and consequently the pressure in the chamber 32 falls, 55 the capsule 31 expands and displaces the slide 34 of the relay device towards the left. The spring 37 then pushes the piston 36 upwards driving the oil from the cylinder 35 through the discharge conduit 39. But in the slow running 60 position of the lever 10 the throttle 2 occupies the slow running position whatever the position is of the piston 36 and the rising movement has no effect on the position of the throttle. The arrangement described thus avoids the reopening 65 of the throttle as is the case with the boost control of the usual devices after a closing movement by the pilot.

This advantage arises each time when the control of maximum opening is not an immediate 70 action control, and in particular when it comprises a relay device.

If namely the boost control illustrated in Fig. 4 is replaced by a speed regulator or governor with a relay device, the device described avoids the 75

re-opening of the throttle by the governor after a closing movement by the pilot.

The arrangement described also has advantages if the boost control is controlled by atmospheric pressure instead of being controlled by the induction pressure (pressure in the induction passage). In this case, the rod 40 is controlled by a manometric capsule exposed to the pressure of the atmosphere (directly or through the intermediary of a relay device). When the height decreases the capsule contracts and normally tends to decrease the opening of the throttle but if the pilot has brought his throttle control lever to the position of closure, the throttle occupies the slow running position and the movements of the capsule are without effect on the throttle. Without this disposition, the pilot's throttle control brought in the slow running position would prevent the contraction of the capsule or the corresponding movement of the power member of the relay device, whereby the whole force developed by the capsule or by the relay device should be applied to the connection members between said capsule or relay device and said pilot's throttle control with a risk of breaking for said members. With the arrangement described, the capsule and/or relay device are free to move, and the closed or slow running position of the throttle always corresponds to the same position of the pilot's throttle control.

In the device illustrated in Fig. 6, the ends of the rods 4 and 5 are compelled to describe arcs of a circle. To this end, the rod 4 is pivotally connected at the axis 43 to the lever 3 mounted on the axis 44 of the throttle (not illustrated). The rod 5 is similarly pivotally connected at the axis 45 to the lever 10 controlled by the pilot. The piston 36 of the relay device of the boost control is connected by a link 46 to the pivoting axis 6 of the two rods. The link 46 could, however, be connected to one or the other rod at a different point from the axis 6. The two rods 4 and 5 have the same length between axes.

The operation of the device is absolutely analogous to the operation of the device illustrated in Figs. 4 and 5 and it can be understood following what has been said above. In Fig. 6, the position occupied by the various members when the lever 10 occupies the slow running position has been illustrated in broken lines. In this position, the throttle itself occupies the slow running position and the axes 43 and 45 are in extensions one of the other. The movements of the piston 36 of the relay device are thus without effect on the opening of the throttle.

In certain cases, it is necessary that the device for controlling the maximum opening should be able to effect the complete closure of the throttle; this is true particularly when the regulating device is a speed governor. It is necessary in this case that the pilot's throttle control should have no effect on the opening of the throttle when the device regulating the maximum opening brings the throttle into the position of total closure (slow running).

The device illustrated in Fig. 7 answers these requirements. It comprises members similar to the members of the device illustrated in Fig. 6 and the corresponding members have been designated by the same reference figures as those in Fig. 6. The only difference is that in the device illustrated in Fig. 7, the length between axes of the lever 10 actuated by the pilot is equal to the length between axes of the rod 5. The link 46 is controlled by a rod 47 sliding in a guide 48 and

connected to the device for regulating the maximum opening (not illustrated), for example to the sleeve of a speed governor. The rod 47 has a shoulder 49 capable of abutting against the upper end 50 of the guide 48.

If the lever 10 controlled by the pilot is maintained in a predetermined position (position illustrated in the drawings) and if the rod 47 of the regulating device descends until the shoulder 49 comes into contact with the stop 50, the rod 47, 10 the link 46, the rods 4 and 5 and the lever 3 occupy the positions 47a, 46a, 4a, 5a and 3a illustrated in broken lines in the drawing. This takes place for example when the device regulating the maximum opening is a speed governor and that the engine has reached or exceeded its maximum permissible speed. The position 3a of the lever 3 corresponds to the closed position of the throttle (slow running).

In the position defined above the pivoting axis 20. 6 between the rods 4 and 5 occupies the position 6a, position in which this axis is to be found in the prolongation of the axis 51 of the lever 10 owing to the equality in length of the lever 10 and the rod 5. Under these conditions, if the pilot moves the lever 10, this movement has the effect simply of pivoting the lever 10 and the rod 5a around the common geometrical axis 6a—51 without affecting the position of the throttle which thus remains in the closed position whatever the position of the control lever 10.

What I claim is:

1. In a device for controlling the throttle of an internal combustion engine both by a pilot's throttle control and by a maximum opening 35 control, the combination of two rods, a pivoting axis for connecting said two rods, an operative connection between one point of one of said rods and the throttle, an operative connection between one point of the other rod and said pilot's throttle 40 control, said connecting points being situated respectively on both rods at an equal distance to said pivoting axis, an operative connection between one of said rods and said maximum opening control, and means for compelling said connecting points of said rods to move respectively 45 along two curves.

2. In a device for controlling the throttle of an internal combustion engine both by a pilot's throttle control and by a maximum opening 50 control, the combination of two rods, a pivoting axis for connecting said two rods, an operative connection between one point of one of said rods and the throttle, an operative connection between one point of the other rod and said pilot's throttle 55 control, said connecting points being situated respectively on both rods at an equal distance to said pivoting axis, an operative connection between one of said rods and said maximum opening control, and means for compelling said connecting points of said rods to move respectively along two curves, said connection between one point of one of said rods and the throttle being so devised that said throttle occupies the slow running position when in projection on a plan 60 perpendicular to said pivoting axis said point is at the point of intersection of said curves.

3. In a device for controlling the throttle of an internal combustion engine both by a pilot's throttle control and by a maximum opening 70 control, the combination of a first pivoting lever operatively connected with said throttle, a second pivoting lever operatively connected with said pilot's throttle control, two rods, a pivoting axis for connecting said two rods, a pivoting axis for 75

JOHAN LICHTENSTEIN. 55
